UNITED STATES PATENT OFFICE

DONALD L. HADLEY, OF MANSFIELD, OHIO, ASSIGNOR TO THE BRYANT ELECTRIC COMPANY, OF BRIDGEPORT, CONNECTICUT, A CORPORATION OF CONNECTICUT

DESIGN FOR AN ELECTRICAL CONNECTER OR SIMILAR ARTICLE

Application filed August 9, 1930. Serial No. 36,612. Term of patent 14 years.

To all whom it may concern:

Be it known that I, DONALD L. HADLEY, a citizen of the United States of America, residing at Mansfield, in the county of Richland and State of Ohio, have invented a new, original, and ornamental Design for an Electrical Connecter or Similar Article, of which the following is a specification, reference being had to the accompanying drawing, forming part thereof.

Figure 1 is a front elevation of an electrical connecter showing my new design applied thereto. The dotted lines in this figure repre-

sent spaces for nuts and screws by which the connecter is held together if it is made in two parts.

Figure 2 is a side elevation of the connecter shown in Fig. 1.

I claim:

The ornamental design for an electrical connecter or similar article, as shown and described.

In testimony whereof I have signed my name to this specification.

DONALD L. HADLEY.
